UNITED STATES PATENT OFFICE.

ROBERT M. TOY, OF JONES STATION, PENNSYLVANIA.

METALLIC TIE AND RAIL FASTENER.

No. 853,043.

Specification of Letters Patent.

Patented May 7, 1907.

Application filed January 9, 1907. Serial No. 351,479.

To all whom it may concern:

Be it known that I, ROBERT M. TOY, a citizen of the United States of America, residing at Jones Station, in the county of Allegheny and State of Pennsylvania, have invented 5 certain new and useful Improvements in Metallic Tie and Rail Fasteners, of which the following is a specification, reference being had therein to the accompanying drawing.

This invention relates to combined metallic ties and rail fasteners, and the invention has for its object to provide a novel tie or rail support particularly designed for a concrete bed or foundation.

15 My invention aims to provide a simple and inexpensive rail support, two of which I use to form a tie or its equivalent. The metallic tie or rail support is constructed to prevent the lateral or vertical displacement of rails, 20 and to dispense with the renewing of an entire tie or sleeper, when one end thereof has been injured or broken.

The detail construction of my improved metallic tie and rail fastener will be presently 25 described and then specifically pointed out in the appended claims, and referring to the drawing forming part of this specification, like numerals of reference designate corresponding parts throughout the several views, 30 in which:

Figure 1 is a perspective view of a rail support and fastener constituting one end of a tie or sleeper, Fig. 2 is an end view of the same, and Fig. 3 is a vertical sectional view.

35 In the accompanying drawing, I have simply illustrated one of the rail supports and fasteners constituting a tie or sleeper, it being apparent that in order to support two rails that form a track, it is necessary to use 40 two of the rail supports and fasteners. In connection with the rail supports and fasteners, I preferably use a concrete bed or foundation, thereby increasing the efficiency and duration of roadbeds and dispensing with the 45 use of ballast commonly employed for retaining ties or sleepers in position.

In the accompanying drawings, I have 50 illustrated a portion of a concrete bed or foundation 1 in which is embedded the lower half of the rail support. The rail support embodies a base plate 2 of substantially the shape of a truncated rectangular pyramid, a central standard or column 3 and a rail chair 4. The chair 4 is formed at its one side with 55 an integral fish bar or plate 5 having a central opening 6 in its web portion. The op-

posite side of the chair 4 is formed with pierced lugs 7 between which is pivotally mounted a fish bar or plate 8 of a less length than the fish bar or plate 5. The fish bar 8 60 has its web portion provided with an opening 9 and adapted to pass through said opening, and the opening 6, is a bolt 10 said bolt passing through the web of a rail 11 seated upon the chair 4. An ordinary nut 12 is then used 65 to lock the rail 11 upon the chair and the fish bar 8 in engagement with said rail. This pyramidal form is designed to impart additional strength to the structure as a firm foundation for sustaining the entire weight 70 of the rail, through the agency of the column 3 and by the chair 4, it being noted that the chair has no contact with or support from the concrete body 1.

From the foregoing description taken in 75 connection with the drawing, it will be observed that the chair 4 is of sufficient length to form a solid seat for a rail and in this connection the parts of my invention may be slightly modified, whereby the confronting 80 ends of two rails can be readily secured upon the chair 4 by simply providing the fish bars 5 and 8 with two sets of openings.

I do not care to confine myself to the material from which the rail support and fastener 85 is made, or to its size and minor details of construction.

Such changes as are permissible by the appended claims, may be resorted to without departing from the spirit and scope of the 90 invention.

What I claim and desire to secure by Letters Patent, is:

In a rail support, and fastener, the combination with a concrete foundation, of a 95 rectangular pyramidal shape base plate, a standard carried centrally thereof, a chair carried by said standard free from contact with said foundation and having an integral fish bar adapted to embrace one side of a 100 rail, a fish bar pivotally mounted at the opposite side of said chair, and adapted to embrace the opposite side of a rail, and means to secure said fish bars to the web portion of a rail, substantially as described. 105

In testimony whereof I affix my signature in the presence of two witnesses:

ROBERT M. TOY.
